DESIGN FOR A MOUNTING FOR A PULLEY-CARRYING MOTOR

William D. Hamerstadt, Indianapolis, Ind.

Application September 9, 1935, Serial No. 58,478

Term of patent 14 years

To all whom it may concern:

Be it known that I, William D. Hamerstadt, a citizen of the United States and a resident of Indianapolis, in the county of Marion and the State of Indiana, have invented a new, original, and ornamental Design for a Mounting for a Pulley-Carrying Motor, of which the following is a specification, reference being had to the accompany drawing, forming a part thereof.

In said drawing, Fig. 1 is a perspective view,

showing the top, one side and one end of a mounting for a pulley carrying motor, showing my new design; and Fig. 2 is a perspective view, showing said top, the other end and the other side, of said mounting.

I claim:

The ornamental design for a mounting for a pulley-carrying motor, as shown.

WILLIAM D. HAMERSTADT.
